UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

ELECTRIC SWITCH.

1,155,814.

Specification of Letters Patent.

Patented Oct. 5, 1915.

Original application filed July 15, 1910, Serial No. 572,123. Divided and this application filed September 1, 1911. Serial No. 647,143.

To all whom it may concern:

Be it known that I, EDWARD M. HEWLETT, a citizen of the United States, residing at Schenectady, county of Schenectady, State of New York, have invented certain new and useful Improvements in Electric Switches, (division of my application filed July 15, 1910, Serial No. 572,123,) of which the following is a specification.

10 My invention relates to electric switches, particularly to switches for opening circuits carrying large amounts of energy, and its object is to provide an improved switch which will open circuits carrying large amounts of energy, and in which the arc formed on separating the contacts is promptly and effectively extinguished.

When an electric switch is connected to a circuit carrying a large amount of energy and particularly if the voltage of the current is high, a persistent and dangerous arc is formed when the contacts of the switch are separated, even though the contacts separate in a vessel containing some suitable insulating fluid, such as oil. In accordance with my invention, the arc formed on separating the contacts is drawn into some suitable device in which insulating fluid is put under great pressure by the arc and on account of its pressure promptly extinguishes the arc. Various devices may be used which tend to disrupt and extinguish the arc when the arc is drawn into them, but the preferred device is a substantially closed pressure retaining vessel mounted in such a position that, as the contacts separate, the arc is drawn into the pressure retaining vessel, whereupon the oil or other insulating fluid in the pressure retaining vessel is put under pressure by the arc and extinguishes the arc. Various forms of arc extinguishing pressure retaining vessels are shown in my application for electric switches, Serial No. 572,123, filed July 15, 1910, of which this application is a division.

My invention will best be understood in connection with the accompanying drawings which merely for purposes of illustration show some of the various forms in which 50 the invention may be embodied and in which—

Figure 1 is a longitudinal section of the form of switch in which the arc is drawn upward into the pressure retaining vessel where it is extinguished; and Fig. 2 is a

longitudinal section of the form of switch in which the arc is drawn downward into the pressure retaining vessel in which it is extinguished.

The same parts in the switches shown in the drawings are indicated in both the figures by the same reference characters.

In the form of switch shown in Fig. 1, a suitable vessel 1, provided with a bottom 2 and a top 3, contains oil or other suitable insulating fluid preferably divided into concentric layers by a concentric barrier 4 of fiber or other suitable insulating material. A number of these barriers may be used, if desired. Where oil is used as the insulating fluid, the tank 1 is filled to bring the level of the oil to the dotted line 5. In the bottom 2 of the particular form of switch shown in Fig. 1, there is mounted an insulator 6 of any suitable construction which carries on the upper end a fixed contact 7 connected to one lead of the circuit to be controlled and coöperating with a movable contact 8 which is movably mounted in an insulator 9 carried in the head 3 of the switch. The movable contact 8 is moved into and out of engagement with the fixed contact 7 in any suitable way, preferably by means of a fluid pressure actuating mechanism such as is outlined in dotted lines in the insulator 9, and comprising a piston 10 rigidly connected to the movable contact 8 and slidably mounted in the cylinder 11, which in turn is carried in the insulator 9. The piston 10 and contact 8 are moved up and down to open and close the circuit by means of compressed air admitted to the cylinder 11 through supply pipes 12, which in turn are controlled by any suitable valve mechanism not shown. The cylinder 11 and piston 10 are connected to the other lead of the circuit and current flows through the cylinder 11, piston 10 and contact 8 into the stationary contact 7 and thence through the circuit. When the contacts 7 and 8 are separated, an arc is formed and in accordance with my invention the arc is extinguished by being drawn into operative relation to an arc extinguishing device, preferably a strong pressure retaining chamber or vessel containing insulating fluid, such as oil, into which the arc is drawn as the switch opens and in which the oil or other insulating fluid put under pressure by the arc is directed against the arc to extinguish it.

In the form of

switch shown in Fig. 1, the arc extinguishing device is mounted on the insulator 9, which carries on the lower end a strong pressure retaining pot or vessel 13 made of 5 any suitable material, preferably metal covered with insulation and provided with an insulating lining 14. The pot 13 is closed at one end by the insulator 9 on which it is mounted and at the other end by an insulating bottom or plate 15, held in position by a flange 16 and perforated by an opening 17 which is of less diameter than the inner diameter of the pot 13. When the switch is opened the contacts 7 and 8 separate in the 10 outer pot 1 and as the contact 8 is moved upward the arc, if it persists, is drawn into the pressure retaining pot or vessel 13 during the last portion of the movement of the contact 8. As soon as the arc is drawn into 15 the pressure retaining pot 13, the oil or other insulating fluid in the pot is at once put under great pressure by the action of the arc, whereupon the arc is compressed and at the same time the oil which flows out of 20 the pressure retaining pot through the opening 17 in the plate 15 is directed against the contact 8 and extinguishes it.

The switch shown in Fig. 2 is constructed with the insulator 6 and fixed contact 7 in 30 the top 3, and the insulator 9 and movable contact 8 in the bottom 2, so that the movable contact moves downward. The insulator 9 carrying the movable contact has on its upper end a pressure retaining pot or 35 vessel 13 constructed and operating in the same manner as the pressure retaining pot 13 of the switch shown in Fig. 1. The pressure retaining pot 13 of the switch shown in Fig. 2 is mounted on the upper end of the 40 insulator 9 which carries the movable contact 8, so that the movable contact 8 draws the arc into the pot 13 near the end of the downward movement of that contact. In order to minimize the disturbance of the oil 45 in the main vessel and to assist in extinguishing the arc, the upper insulator 6 is provided on the lower end with a bell 18 which surrounds the fixed contact 7 and tends to trap or hold the arc gases generated as the 50 contacts separate so that the arc gases will not spread out through the oil or other insulating fluid and cause an arc to be established between the fixed contact and the walls of the vessel 1. In this form of switch 55 the arc is extinguished by the action of the fluid put under pressure by the arc in the pressure retaining pot 13, in the same manner as in the switch shown in Fig. 1. Disturbance of the oil in the vessel 1 is reduced 60 to a minimum by the concentric barrier 4 surrounding the movable contact 8, so that the main body of oil in the vessel 1 is not disturbed by oil ejected from the pressure

retaining vessel because the ejected oil is restrained by the barrier 4.

65

My invention may be embodied in many other forms than that shown and described, and I therefore do not limit myself to the precise arrangement disclosed, since various modifications of my invention will suggest 70 themselves to those skilled in the art without departing from the spirit of my invention, the scope of which is set forth in the annexed claims.

What I claim as new and desire to secure 75 by Letters Patent of the United States, is,—

1. An electric switch comprising an outer vessel adapted to contain insulating fluid, a stationary contact mounted in said vessel, an inner pressure retaining vessel mounted in 80 but insulated from said outer vessel and having an opening in one wall thereof, and a movable contact mounted in said inner vessel to move through the opening in said vessel into engagement with said stationary 85 contact, said inner vessel being positioned to inclose said movable contact as said movable contact reaches its final position as the switch opens.

2. An electric switch comprising an outer 90 vessel containing insulating fluid, a stationary contact mounted in one end of said vessel, an insulator projecting into the other end of said vessel, an inner pressure retaining vessel mounted on said insulator and 95 having an opening in one wall thereof, and a movable contact slidably mounted in said insulator to pass through said inner pressure retaining device and through said opening to coöperate with said stationary 100 contact whereby said movable contact passes through said opening and into said pressure retaining vessel during the latter portion of its movement as the switch opens.

3. An electric switch comprising an outer 105 vessel containing insulating fluid, a stationary contact mounted in said outer vessel, a pressure retaining vessel mounted in but insulated from said outer vessel and having an opening in one wall thereof, and a movable contact mounted in said pressure retaining vessel to move through the opening in said vessel to coöperate with said stationary 110 contact, said pressure retaining vessel being mounted in said outer vessel near the 115 end of the path of opening movement of said movable contact in position to cause said contact to pass through said opening and reach its final position in said pressure retaining vessel as the switch opens.

In witness whereof, I have hereunto set my hand this 31st day of August, 1911.

EDWARD M. HEWLETT.
